UNITED STATES PATENT OFFICE.

CHARLES S. WEBER, OF SAN JOSÉ, CALIFORNIA.

TENSIONAL SOUND-BOARD.

SPECIFICATION forming part of Letters Patent No. 402,496, dated April 30, 1889.

Application filed March 3, 1887. Serial No. 229,555. (No model.)

To all whom it may concern:

Be it known that I, CHARLES S. WEBER, a citizen of the United States, residing at San José, in the county of Santa Clara and State 5 of California, have invented certain new and useful Improvements in Tensional Sound-Boards; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to sound-boards for musical instruments, principally for pianos and other analogous stringed instruments.

The improvements consist in having the ordinary sound-board put under tension in the 20 direction of the length of its fibers, which is found to increase the sonority of the same to an eminent degree. As it is a desideratum to have the sound-board made of as thin material 25 as possible, a number of such sound-boards may be arranged in a pile one above each other, in case one is not sufficient to withstand the pressure of the strings. By having the sound-board under tension the pressure of the strings is sustained without the help of 30 the bridge-pins or any other contrivance.

The improvements consist in the novel features presently to be described and claimed, and shown in the annexed drawings, in which—

35 Figure 1 is a detail side view of a musical instrument embodying my invention. Fig. 2 is a modified form.

Referring to Fig. 1, D is the frame, between 40 which the sound-board A is supported and the strings C strung. The strings extend over the bridge G and are secured at one end to the frame by the hitch-pin I and at the opposite end by the turning-pin E. The agraffe F and hammer H are of ordinary construction and 45 operation.

The gist of the invention is in having the sound-board under tension in the direction of the length of its fibers, and for accomplishing this result the sound-board is adjustably sup-

ported between the frame, so that any slack 50 may be taken up.

The clamps B, which connect the sound-board and frame, are bifurcated at their outer ends and embrace the edges of the sound-board, to which they are secured by the bolts 55 b. One of the clamps has the threaded shank b' extended through the frame and provided on its outer end with the nut e, by which the tension on the sound-board can be regulated. There may be as many of the clamps as occasion 60 may require, or each clamp may extend the whole length of the sound-board from side to side along each end, and may have as many threaded shanks as desired.

The ends of the sound-board are thickened 65 and the arms of the clamp correspondingly converge, as shown, which renders more certain the binding between the clamp and board.

Fig. 2 shows the ordinary sound-board, J, 70 re-enforced by the sound-board K, mounted by my improved method.

Having thus described my invention, what I claim, and desire to secure by Letters Patent, is—

1. The combination, with the frame and the sound-board, of the clamps adjustably connecting the sound-board with the frame, whereby the linear tension upon the fibers composing the sound-board can be varied, 75 substantially as set forth.

2. The combination, with the frame and the sound-board having its ends thickened, as shown, of the clamps having bifurcated ends conforming to and embracing the thickened 80 ends of the boards, substantially as set forth.

3. The combination, with the frame and the sound-board having thickened ends, of the clamp fitted to the thickened ends, and the threaded shank passed through the frame, 85 and the nut mounted upon the threaded end, substantially as specified.

In testimony whereof I affix my signature in presence of two witnesses.

CHARLES S. WEBER.

Witnesses:

H. J. ALEXANDER,
J. E. FISHER.
